UNITED STATES PATENT OFFICE.

JOHN LIONEL SHAFER, OF JOPLIN, MISSOURI.

PUMP.

Application filed October 15, 1923. Serial No. 668,681.

To all whom it may concern:

Be it known that I, JOHN LIONEL SHAFER, a citizen of the United States, and resident of Joplin, in the county of Jasper and 5 State of Missouri, have invented certain new and useful Improvements in Pumps, of which the following is a specification.

This invention relates to pumps and the operating means therefor and is an improvement 10 on the construction illustrated in United States Patent #1,400,188, issued December 13, 1921.

Briefly stated an important object is to provide a pump and operating means therefor for use in mines and other places where the power unit cannot be conveniently placed close to the pumping mechanism.

Further an important object is to provide a novel equalizing mechanism by means of 20 which the pressure and quantity of liquid in the several conduits is equalized.

Also, the invention forming the subject matter of this application aims to provide a pumping mechanism of the character specified 25 which employs standard couplings and other parts so far as practical so as to reduce the cost of production to a minimum.

Other objects and advantages will be apparent 30 during the course of the following description.

In the accompanying drawings forming a part of this application and in which like numerals are employed to designate like parts throughout the same,

35 Figure 1 is a side elevation illustrating the power unit.

Figure 2 is a detail sectional view through a valve embodied in the invention.

40 Figure 3 is a detail longitudinal sectional view through one of the primary pumps.

Figure 4 is a sectional view through an equalizing mechanism.

45 Figure 5 is a sectional view through a pump embodied in the invention and which is operated by the construction illustrated in Figure 1.

Figure 6 is an end view of the pump, parts being shown in section.

50 Figure 7 is a fragmentary plan view of a valve embodied in the invention.

In the drawing wherein for the purpose of illustration is shown a preferred embodiment of the invention the numeral 5 generally designates a base upon which a pair of 55 aligned cylinders 6 are secured and Figure 3 illustrates that a piston 7 is slidable in each

cylinder so as to cause fluid in the conduits 8 and 10 to move back and forth under the influence of the pistons. That is to say the conduits 8 and 10 are connected to the outer ends of the cylinders 6 and when the pistons 7 are reciprocated the fluid in the conduits will be moved back and forth for operating a pump to be fully hereinafter described.

Figure 1 illustrates that the pistons 7 have 60 connection with a rod 14, the intermediate portion of which is provided with an enlargement 16 through which a pitman rod 17 is connected. One end of the pitman rod is connected to a crank 18 mounted on a 65 shaft 19 and the shaft 19 has connection through the medium of gears 20 and 21 with a power transmitting wheel 22. A belt or other power transmitting means may be connected to the wheel 22 so as to operate the 70 primary pump and thereby force the fluid back and forth in the conduits 8 and 10.

75 In carrying out the invention the elbows 23 and 24 which join the conduits to the outer ends of the pistons are provided with 80 replenishing pipes 26 in which one way valves 27 are interposed. The pipes 26 have connection with a reservoir 28 through the medium of a pipe 30 and when the supply 85 of fluid in one of the conduits drops below a predetermined point the flap in one of the valves 27 is opened and a quantity of fluid is supplied to the conduit. In other words when the pressure of the fluid in one of the conduits drops below the pressure of the 90 water in the reservoir 28 additional water is supplied from the conduit. In this manner lost motion of the moving parts of the pump is reduced to a minimum and consequently the efficiency of the mechanism is 95 maintained at a high point. However, in carrying out the invention additional reservoirs and one-way valves may be connected to the conduits at any point between the primary and secondary pumps so that the 100 water supply may be replenished at any point. This is especially useful where the secondary pump is located a substantial distance from the primary pump.

With reference to Figure 5 it will be 105 observed that the conduits 8 and 10 are connected to the outer ends of cylinders 37 and the inner ends of the cylinders 37 are joined through the medium of bolts 38 and flanges 39 to a pump casing 40.

110 The end portions of the cylinders 37 are provided with flanges 140 which flatly abut

the flanges 42 of elbows 43 and the flanges 140 and 42 are joined by fastening devices 44. The pump casing 40 is provided with heads 46 and 48 and Figure 5 illustrates that 5 valve supporting walls 50 are confined between the pump casing and the heads 46 and 48 and the said valve supporting walls 50 cooperate with the casing 40 in defining an enclosure in which a quantity of liquid is 10 confined.

More specifically the pump casing is divided by means of a transverse partition 52 into two chambers 53 and it will be seen that the member 52 not only constitutes a partition but also acts as a supporting means for 15 a central cylinder 54.

The heads 46 and 48 are provided with chambers which communicate with the chambers 53 through the medium of openings 57 in the valve supporting plates 50 and the said openings are normally closed by valves 58. The valves 58 are urged to their closed positions by means of springs 59 and when the pressure is in one direction the 20 valves are opened and when the pressure is in the other direction the valves are closed.

The heads 46 and 48 have connection with a suction or inlet pipe 60 while the heads 46 have connection with an outlet pipe 61 30 which may extend to a suitable point of discharge.

The water in the conduits 8 and 10 acts on auxiliary pistons 64 slideable in the cylinders 37 and the pistons 64 have connection with a 35 pair of piston rods 66 the inner portions of which are joined to a main piston 67 slideable in the cylinder 54. It will be seen that when the main piston 67 is reciprocated the volume of one of the chambers 53 is de- 40 creased and the volume of the other chamber is increased and consequently a pumping action takes place. When the piston is moved to the left one of the inlet valves 59 is closed and the other is opened so that 45 liquid may be sucked into one of the chambers.

Simultaneously with this, one of the outlet valves 58 is closed and one is opened so that the liquid pumped out of one of the chambers 53 is directed into the discharge head 46.

Each cylinder 37 is provided with a tubular extension 69 which extends into the chamber 53 and constitutes a guide for a spring 70 arranged in the path of travel of 55 the main piston 67 so as to cushion the action of the same.

An additional equalizing mechanism is illustrated in Figure 4 wherein the numeral 75 designates a pipe establishing communication between the conduits 8 and 10 and T-couplings 76 are interposed in the pipe 75 and have connection with the ends of a by-pass pipe 77. Figure 4 clearly illustrates the by-pass pipe 77 and associated elements 60 and also indicates that the pipe 75 is pro-

vided with a one-way valve 78 which allows the excess liquid in one of the conduits to pass through the pipe 75 and into a pressure relief valve 80.

The by-pass pipe 77 is provided on opposite sides of the relief valve 80 with one-way valves 81 and 82 which allow the liquid which passes through the relief valve from one conduit to pass into the other conduit and thereby maintain the liquid in the several conduits more or less equalized. 75

Assuming there is an excess quantity of liquid in the conduit 8 the one-way valve 78 at the upper right hand corner of Figure 4 will be opened and the other valve 78 in the pipe 75 will remain closed. Therefore the liquid will flow into and through the spring actuated relief valve 80 and the liquid will flow through the one-way valve 82 and again into the pipe 75 so that the liquid will 85 enter the conduit 10. Of course if there is an excess quantity of liquid in the conduit 10 it will flow into the conduit 8.

In operation the pump rods 14 may be 90 operated either by power or by hand so as to reciprocate the pistons 7 and this will cause the liquids in the conduits 8 and 10 to flow back and forth. This movement of the liquid in the conduits 8 and 10 will reciprocate the pistons 64 so that the corresponding movement is imparted to the main piston 67. The movement of the main piston 67 and the pressure actuated pistons 64 will vary the volume of the chamber 53 100 so that a pumping action takes place in the said chambers whereby the liquid is pumped through the pipe 60 and out through the pipe 61.

In conclusion it is desired to point out 105 that the invention forming the subject matter of this application is capable of use in connection with any make and design of reciprocating pump. There are a great many different designs of reciprocating pumps designed to be operated by direct power by attaching the pump piston direct to a steam engine, or by a connecting rod to a crank shaft of some other power unit and in this case the power is necessarily installed with the pump. 110 115

In accordance with this invention the pump may be located at a point remote from the source of power and by the pressure in the conduits 8 and 10 the pump may be operated. 120

Practically all reciprocating pump cases are formed with openings at opposite ends of the pump cylinder, one end being open for the stuffing box or connecting rod and the other end being open for removing or 125 packing the piston or plunger. However all pumps do not have the same sized openings at both ends, but both ends are spaced, drilled and tapped for flanged connections and it is one of the principal objects of this 130

invention to so form the flanges 39 of the cylinders 37 so that they may be connected to the spaced ends of the pump casing. In other words when modifying a standard 5 pump case for use in connection with this invention the members connected to the spaced ends of the casing are removed and cylinders 37 with the proper size flanges 39 are fitted.

10 When the parts are assembled as illustrated in Figure 5 the reciprocating pump may be operated from a remote point and at any angle from the power.

Having thus described the invention, what 15 is claimed is:—

1. In a pump, a pair of pressure conduits, a pipe connecting said conduits, a by-pass pipe connected at its end and at its intermediate portion to said first named 20 pipe, and one-way valves located in the first named pipe and in the bypass pipe between the end and intermediate connection.

2. A pump of the character specified comprising a pair of pressure conduits, 25 pumping cylinders connected to said conduits, a pipe connected to said conduits, a by-pass pipe connected at its ends to said first named pipes and having spaced one-way valves, said first named pipes being 30 provided with one-way valves between the ends of said by-pass pipe, and a relief valve establishing communication between the intermediate portions of said first and second named pipes and being located between 35 the valves in the pipes.

3. A pump of the character specified comprising a pair of pressure conduits, pumping cylinders connected to said conduits, a pipe connected to said conduits, a by-pass pipe connected at its ends to said 40 first named pipes and having spaced one-way valves, said first named pipes being provided with one-way valves between the

ends of said by-pass pipe, a relief valve establishing communication between the 45 intermediate portions of said first and second named pipes and being located between the valves in the pipes, and a reservoir having pipes connected to said conduits.

4. A pump of the character specified comprising a pair of pressure conduits, pumping cylinders connected to said conduits, a pipe connected to said conduits, a by-pass pipe connected at its ends to said first named pipes and having spaced one-way valves, 50 said first named pipes being provided with one-way valves between the ends of said by-pass pipes, a relief valve establishing communication between the intermediate portions of said first and second named pipes 55 and being located between the valves in the pipes, and a reservoir having pipes connected to said conduits, the pipes of said reservoir being provided with one-way valves. 65

5. In combination, a pump having a working piston, actuating pistons connected to the working piston of said pump, cylinders for said actuating pistons, pressure pipes connected to said cylinders and containing 70 columns of fluid, means for pulsating said columns of fluid whereby to reciprocate the actuating pistons and consequently reciprocate the working pistons of the pump, means connected with the pressure pipes 75 for replenishing automatically the supply of fluid in the pressure pipes, and an equalizing arrangement between the pressure pipes including an equalizing pipe connecting said pressure pipes, a bypass connected at its 80 ends and at its intermediate portion to said equalizing pipe and one-way valves located in the first named pipe and in the bypass pipe between the end and intermediate connections.

JOHN LIONEL SHAFER.
